UNITED STATES PATENT OFFICE.

CARLOS PEREIRA PINTO, OF BUENOS AIRES, ARGENTINA.

REVOLVER AND SIMILAR ARM.

1,342,923.

Specification of Letters Patent. Patented June 8, 1920.

Application filed November 22, 1919. Serial No. 339,889.

To all whom it may concern:

Be it known that I, CARLOS PEREIRA PINTO, citizen of the Brazilian Republic, residing at 629 Reconquista street, Buenos Aires, Argentina, have invented certain new and useful Improvements in Revolvers and Similar Arms, of which the following is a specification.

This invention relates to certain improvements in revolvers and similar arms, and has for its object to provide a suitable means adapted to secure the aim by avoiding the trouble caused by the muscular effort exerted at the instant of firing.

It is a well known fact that in connection with revolvers, firing is performed by exerting muscular pressure on the trigger which by receding, causes the rise of the percussion cock and its immediate release or fall, in one single movement, by the action of the springs which operate to propel the same. This muscular effort causes the gun to move so as to deviate the aim at the very instant of firing. When effecting several consecutive discharges, the above mentioned deviating movement is even increased by the movement caused by the recoil of the gun, owing to the explosion of the cartridges.

This objectionable feature inherent in the revolvers actually in use, is eliminated by my invention which essentially consists in making use of a double action in firing, the latter being effected by two separate or independent operations, that is to say, by the first operation which requires a strong muscular effort to be exerted on the trigger, the percussion cock is raised to its highest position in which it remains locked, and by the second operation which only requires a very gentle pressure to be applied to the trigger, the fall or release of said percussion cock, and hence the discharge of the cartridge, is produced.

For the first pressure applied to the trigger, the muscular effort need not be measured; whatever be the degree of force used, the only result obtained at this first step of the operation, is that the trigger will be caused to travel along its entire stroke, thereby carrying the percussion cock to its highest position where it remains locked; in consequence, by this single operation, the discharge cannot take place. In order to obtain the release or disengagement of the percussion cock to cause firing, it will be necessary to relieve the pressure applied to

the trigger, so as to allow of the same returning to its initial position; thereupon, a slight pressure applied to said trigger, will cause the percussion cock to fall and fire. 60

In consequence, it follows that when performing the heavy muscular effort which moves the gun and interferes with aiming, firing does not, and cannot, occur, but the gun is simply prepared for firing. The operation proper of firing the cartridge only requires a simple pressure on the trigger which being very gentle, does not cause any movement of the gun. 65

Besides the advantage of enabling the shooter to secure the aim, this invention affords a greater security in the handling of the gun since it becomes absolutely impossible that a discharge should result from a first or initial pressure applied to the trigger. 70 75

The percussion cock may also be raised by carrying the same by hand to its highest or locked position, and it may also be lowered slowly, by holding the trigger with the hand.

This invention does not specially relate to 80 any particular mechanical arrangement, but consists in the adoption of means, which when operated by the pressure exerted on the trigger, raises the percussion cock and carries the same to the highest point of its travel 85 where it remains locked or engaged; on relieving the pressure from the trigger, this latter will return to its forward position, whereupon, a further pressure applied thereto will disengage the percussion cock to 90 allow the same to fall and fire the cartridge.

The invention may be applied to any known or novel type of revolver by providing the same with the necessary additional parts or by modifying the parts already existent in order to obtain the desired results. 95

A preferred embodiment of this invention is shown by way of example in the accompanying drawings, in which:

Figure 1 illustrates the firing mechanism 100 of a revolver of well known construction, with the parts in their normal position, said revolver being provided with the necessary means and parts of novel design for carrying the present invention into practice. 105

Fig. 2 illustrates the trigger and percussion cock with the auxiliary parts, according to this invention, in the position in which the trigger commences to actuate the percussion cock. 110

Fig. 3 is a similar view, showing the percussion cock in a somewhat more raised po-

sition by the action of the trigger, at the moment at which it commences to strike against the locking piece of the percussion cock.

Fig. 4 shows the percussion cock locked in its raised position and the locking piece or catch prepared for disengagement by a further operation on the trigger which meantime has moved forward to assume its initial position.

10 Fig. 5 illustrates the second stage of the operation of the trigger at the instant in which the percussion cock is disengaged and fires the gun.

15 In all the said figures, the same numbers of reference indicate like or corresponding parts.

1 is the percussion cock provided at its tail end with an abutment 2 and a projection 3, for a purpose hereinafter to be explained. 4 is the trigger, provided with its corresponding spring 5 which tends to maintain the same in its normal position. On said trigger is formed an operative projection 6, intended to raise the percussion cock by placing itself below the abutment 2, and a notch 7 within which engages the operating lever 8, pivoted at 9, whose opposite end is provided with a notch 10 into which enters the projection 3 of the tail of the percussion cock, for the purpose of locking the latter in its raised position after the first or pre-

liminary movement of the trigger has been performed.

A spring 12 tends to hold the said lever 8 in its uppermost position, by the end in 13 which the notch has been formed.

A detailed description of the working of the device is deemed unnecessary, as the same will be readily understood by referring to the illustrative drawings.

I now declare that what I claim and desire to secure by Letters Patent, is:—

In a fire arm, the combination of a spring-actuated hammer; a spring-controlled trigger adapted at the commencement of a single pull to directly engage the hammer and rock it into cocked position, and at the conclusion of such pull to release the hammer and return to normal position; and a locking member adapted to automatically engage the hammer when the latter moves into cocked position so as to hold it in that position; said locking member being directly engaged and operated by the trigger when the latter is pulled a second time, whereby said locking member is released from the hammer to permit automatic firing movement of the hammer under the influence of its actuating spring.

In testimony whereof I affix my signature.

CARLOS PEREIRA PINTO.
